DEVICE FOR PROVIDING CARBON DIOXIDE UNDER PRESSURE

Original Filed April 24, 1931

UNITED STATES PATENT OFFICE

1,957,640

DEVICE FOR PROVIDING CARBON DIOXIDE
UNDER PRESSURE

Joseph Grison, New York, N. Y.

Application April 24, 1931, Serial No. 532,424
Renewed February 12, 1934

7 Claims. (Cl. 62—91.5)

This invention relates to devices for supplying carbon dioxide in gas or liquid form under pressure, and more particularly to means for facilitating the production and transporting of such 5 carbon dioxide.

It is the present custom to supply carbon dioxide in liquid form in heavy metal containers under a pressure of 1000 pounds to 1200 pounds per square inch. The carbon dioxide is converted 10 into the liquid form at a central plant, and transported to the places where it is to be used in metal containers. Obviously, such a method of transportation is inconvenient and expensive and undesirable, especially in view of the high 15 pressure of carbon dioxide. It is well known that carbon dioxide may be easily solidified and compressed into blocks of any size, and that when solidified carbon dioxide sublimes, the gas has approximately 500 times the volume of the solidified carbon dioxide. It is also known that a 20 quantity of solidified carbon dioxide may be placed into a suitable container and allowed to sublime or change to the liquid state and produce a high pressure. However, such practices have 25 been carried on in compartments which do not enable the replenishing of the supply of solidified carbon dioxide without materially affecting the pressure of the liquid carbon dioxide already formed.

30 It is therefore an object of this invention to provide a container in which solidified carbon dioxide may be readily converted into liquid or gas under pressure, and the solidified carbon dioxide replenished from time to time without 35 affecting the pressure of the liquid or gas already formed.

A further object is the provision of a container 40 for converting solidified carbon dioxide into a liquid or gas, in which container is provided a safety valve to allow the escape of the gas when the pressure exceeds a predetermined amount.

These and other advantageous objects are attained by the novel construction, combination and arrangement of parts hereinafter described and 45 shown in the accompanying drawing, constituting a material part of this disclosure, and in which:

Fig. 1 is a sectional view of the container for 50 converting solidified carbon dioxide into gas or liquid.

Fig. 2 is a sectional view taken on line 2—2 of Fig. 1.

Fig. 3 is a sectional view taken on line 3—3 of Fig. 1.

55 Referring to the drawing, in Fig. 1, is shown

a metal container 5, having walls strong enough to withstand at least 2000 pounds per square inch pressure. The container 5 is preferably cylindrical in shape, and is provided with a cover 6, hinged thereto. At a short distance 39 from the open end of the container is mounted a plate 11, having shoulders upon which rests a heavy wire grating 7 and forming a small chamber 8 in which is placed a definite weight of solidified carbon dioxide 9. The chamber 8 is 65 provided also with a safety valve 10 to accommodate excessive pressures, the valve 10 being of substantially the same structure as the safety valve 16, hereinafter described.

The plate 11 has a central aperture 14 through 70 which gas passes into the main compartment 21. The plate 11 also has a wedge-shaped recess adjacent the aperture 14, the recess 12 being shaped to receive a wedge-shaped valve plate 13 to close the aperture 14 and prevent the escape of gas 75 from compartment 21 when the cover 6 is raised to replenish the supply of solidified carbon dioxide in chamber 8. The valve plate 13 has a threaded stem movable in a threaded portion of the plate 11 and the wall of container 5, the valve being 80 controlled by a hand wheel 15.

Mounted in a wall of the compartment 21 is a safety valve 16 having a passage 17 communicating with the compartment 21, which passage is normally held closed by a conical nose 18 of 85 a block or plunger 19 having a recess receiving one end of a compression spring. When the pressure in the compartment 21 exceeds the strength of the spring, the nose 18 is moved to open the passage 17 and allow the gas to escape 90 through an aperture 20 in the valve casing.

Gas or liquid carbon dioxide may be drawn 95 from compartment 21 through an aperture in the bottom of container 5, which aperture is controlled by a valve 22; or it may be drawn through tube 26, which communicates with a casing 24 containing lumps of calcium chloride 25 to remove the moisture from the gas before it is finally drawn through either of the pipes 27 or 28. The casing 24 is mounted directly on the container 100 5 by means of lugs 23, which are integral with the container and the casing. The pipes 27 and 28 may be used to supply gas under pressure simultaneously to a carbonating apparatus for soda fountain use or to a machine for converting the carbon dioxide back into small discs of solidified carbon dioxide.

In operation, a definite weight, for example 100 lbs., of solidified carbon dioxide is placed in the chamber 8 and rests on the grating 7. The 110

aperture 14 is uncovered by moving the wedge-shaped valve 13 as above described. The cover 6 is placed in position and securely held by means of bolts or the like. As the heat of the surrounding atmosphere is conducted through the walls of the container 5 to the block of solidified carbon dioxide 9, the latter sublimes, and inasmuch as carbon dioxide has a density greater than air, the gas passes downwardly through the aperture 14 into the compartment 21. By using a definite quantity of solidified carbon dioxide, a substantial definite pressure of gas or liquid carbon dioxide may be obtained.

When it is desired to replace the supply of solidified carbon dioxide in the chamber 8, the valve plate 13 is moved to cover the aperture 14 and prevent the escape of gas from the compartment 21 when the cover 6 is raised. This feature is of considerable importance, as otherwise it would be impractical to maintain the pressure in the compartment 21 or replace the supply of solidified carbon dioxide without the loss of considerable amount of gas which would rush out of the container at a great rate due to the high pressure.

By providing a safety valve 16, the pressure of the gas in the compartment 21, may be controlled and would prevent accidents due to negligent maintenance of the device.

From the above description it will be seen that there has been produced a simple and effective apparatus for conveniently supplying carbon dioxide under pressure without necessitating waste or losses during the manipulation of the apparatus.

The foregoing disclosure is to be regarded as descriptive and illustrative only, and not as restrictive or limitative of the invention of which obviously an embodiment may be constructed including many modifications without departing from the general scope herein indicated and denoted in the appended claims.

I claim:—

1. A device for producing liquid carbon dioxide, comprising a container, a plate dividing the container into a small compartment and a large compartment, means for introducing solidified carbon dioxide to the small compartment, said plate having an aperture through which gas passes from the small compartment to the large compartment, and means for covering the aperture in the plate.

2. A device for producing liquid carbon dioxide, comprising a container having a small compartment and a large compartment, means for

enabling the passage of gas from the small compartment to the large compartment, and means controlled from the outside of the container to prevent the flow of gas from one compartment to the other.

80

3. A device for producing carbon dioxide under pressure, comprising a container having a small compartment to hold a quantity of solidified carbon dioxide and a large compartment to receive carbon dioxide under pressure, said compartments normally communicating with each other, means to hermetically seal the container, and means controlled from the outside of the container to prevent the flow of gas from one compartment to the other.

85

4. A device for producing carbon dioxide under pressure from solidified carbon dioxide, comprising a container having a small compartment to receive a quantity of solidified carbon dioxide and a large compartment to receive carbon dioxide under pressure formed by the sublimation of the solidified carbon dioxide, said compartments normally communicating with each other, and means to prevent the flow of gas from one compartment to the other.

90

5. A device for producing carbon dioxide under pressure from solidified carbon dioxide, comprising a container, a plate in the container dividing the latter into a small compartment to receive a quantity of solidified carbon dioxide and a large compartment to receive carbon dioxide under pressure formed from the sublimation of the solidified carbon dioxide, said plate having an aperture therein, and means to close the aperture.

95

6. A device for producing carbon dioxide under pressure from solidified carbon dioxide, comprising a container having an upper compartment and a lower compartment, said compartments normally communicating with each other, and means controlled from the outside of the container to prevent the flow of gas from one compartment to the other.

100

7. A device for producing carbon dioxide under pressure from solidified carbon dioxide, comprising a container having a first compartment to receive a quantity of solidified carbon dioxide and a second compartment to receive carbon dioxide under pressure formed by the sublimation of the solidified carbon dioxide in the first compartment, said compartments normally communicating with each other, and means controlled from the outside of the container to prevent the flow of gas from one compartment to the other.
